Inventor:
Isaac P. Owens

UNITED STATES PATENT OFFICE.

ISRAEL P. OWENS, OF GAINESVILLE, TEXAS.

THILL-COUPING.

SPECIFICATION forming part of Letters Patent No. 366,976, dated July 19, 1887.

Application filed June 10, 1886. Serial No. 294,776. (No model.)

To all whom it may concern:

Be it known that I, ISRAEL P. OWENS, a citizen of the United States, residing at Gainesville, in the county of Cooke and State of Texas, have invented a new and useful Improvement 5 in Thill and Tongue Couplers for Buggies, Hacks, Carriages, and all Vehicles that have not Platform-Springs, of which the following is a specification, reference being had to the 10 accompanying drawings, forming part thereof.

In my invention I aim to unite neatness, strength, durability, and convenience, the chief object of my coupler being the speedy and convenient interchanging of thills and 15 tongue, as will hereinafter be shown.

Figure 1 is a perspective view of the entire coupler and clip connected ready for use. Fig. 2 is a view of the entire coupler in separate sections, giving a separate view of each part. 20 Fig. 3 is a horizontal section of Fig. 1.

Similar letters refer to similar parts throughout the several views.

The check-pieces A t and clip P are made solid, as shown in Fig. 2, with plate D at bottom 25 and top, forming anti-rattler bed. The small hole in groove L on check-piece A, as shown in Fig. 2, is for pin m to pass through from the inside of anti-rattler bed, and upon which the lever B rests when placed in position, as shown 30 in Fig. 3. This pin m, pressing against anti-rattler n, forms the spring for clasping slide-plate e, when said plate is shoved back until catch J comes into notch s on lever B. This securely locks the entire coupler. This lever 35 B is hinged in the end of bolt K, as shown in Figs. 2 and 3, and is used as a handle for inserting and drawing out the bolt which holds the thills and tongue when in operation. It also forms the lock and key, which securely 40 holds the bolt in its place when in use without the aid of a nut.

In operating this coupler, press the knob B, as shown in Fig. 1, back until it will allow slide-plate e, which works in a dovetail, to 45 draw out until it comes against check-screw i in the end of check-piece A, disclosing the

bolt K, which holds the thills or pole, raise the lever or handle B, as has been previously mentioned, out of groove L to a line with bolt K, press the thills or pole back, and draw out 50 the bolt. The groove h on the inside of slide-plate e, as shown in Fig. 2, allows it to pass over check-screw i in the end of check-piece A, as previously referred to. It also gives space for lever B in clasping. The hole for 55 bolt K in check-piece t may be made only about five-sixths of the way through, leaving a shield upon the outside, and slide-plate e forming the same on the inside, thus inclosing the bolt from view, and preventing its escape from its 60 proper place—the bolt securing the thills, the thills securing anti-rattler, anti-rattler securing the clasp, the clasp securing the bolt, thus forming a combined lock. Groove L is 65 cut dovetail.

This coupler can be used on all buggies, hacks, &c., now in use without the changing or remodeling of thill or tongue irons.

I claim as my invention—

1. A thill-coupling comprising perforated 70 check-pieces A and t, and a coupling-bolt having a locking-lever hinged thereto and adapted to be secured in a recess in the check-piece A, substantially as described.

2. A thill-coupling comprising perforated 75 checks A and t, a coupling-bolt, a locking-lever hinged to said bolt, a recess in the check A, and a cover-plate adapted to fit said recess and secure the locking-lever, substantially as described.

3. A thill-coupling comprising perforated 80 checks A and t, a coupling-bolt, a locking-lever hinged to said bolt, said lever being provided with knob B and notch s, a cover-plate having groove h and catch J, and a spring-pin, 85 m, adapted to hold the lever and cover in engagement, substantially as described.

ISRAEL P. OWENS.
